AIRPLANE TOY

William Lines, Yonkers, N. Y.

Application December 16, 1943, Serial No. 514,456

9 Claims. (Cl. 46—175)

This invention relates to toys, and more particularly to a toy made in the form of an airplane and adapted to be held in the hands, said toy including means by which propeller rotation, the noise of the motor and the sound of machine gun fire may be simulated.

The invention contemplates the provision of a toy of this character provided with a hand-crank and means driven therefrom to rotate a propeller and cause a sound, in simulation of the noise of an airplane motor, to be produced. The invention also contemplates the provision of a trigger and elements associated therewith and co-operating with the crank-driven means, by which the sound of machine gun fire may be simulated whenever desired.

The object of the invention is to provide an interesting, useful toy of the character described.

In the accompanying drawing, wherein an illustrative embodiment of the invention is disclosed, Fig. 1 is a side elevation of a toy constructed in accordance with the invention; Fig. 2 is a plan view of the same, with parts fragmentarily shown to disclose construction; Fig. 3 is a sectional view on the line 3—3 of Fig. 1, looking in the direction of the arrows; Fig. 4 is a sectional view on the line 4—4 of Fig. 2, looking in the direction of the arrows, and Fig. 5 is a side view of the forward end of the toy, showing the noise-making device for simulating airplane motor sound.

In the drawing, 1 indicates the body of the toy, the same being of a shape to resemble the body or fuselage of an airplane. At the rear of the body 1 is a piece 2 which rises from the top of the body and is shaped to simulate an airplane rudder. Secured across the top of the body 1 near its forward end, and by any suitable fastening means, and particularly by one which permits its detachment when desired, is the wing 3. At 4 is shown a loop, preferably of wire or the like, provided with a stem portion 5 which removably fits into an aperture in the top of the body 1 and through the wing 3. The loop 4 is intended to be used as a simulation of a machine-gun sight.

At 6 is shown the propeller, provided with a hub 7 secured on the propeller shaft 8 rotatively mounted in the nose of the body 1. Secured on the propeller shaft 8 is a pulley 9, rotative in the aperture 10 formed in the body 1 to provide clearance for said pulley 9. Projecting laterally from one side of the body 1 are spaced lugs 11 and 12, located respectively above and below the aperture 10, said lugs constituting bearings for a spindle 33 on which rollers 13 are freely rotative, said rollers being held in spaced relation by means of the bushing 34 fixed on the spindle 33.

Extending through the body 1 near its rear end is a rotatable shaft 16. Secured at one end of said shaft 16 is a pulley 15, and extending about the pulley 15 is a drive cord or other flexible driving member 14 which also extends around the rollers 13 and around the propeller-shaft pulley 9. From this arrangement it will be seen that when the shaft 16 is rotated, it will communicate such rotative movement to the propeller shaft 8 so that the propeller thereon will be revolved.

For imparting rotative movement to the shaft 16, a crank 17 is provided on said shaft, the crank having a knob 18 by means of which it may be conveniently engaged by the hand. A handle 19 projects downwardly from the body 1 so that the toy may be supported by this handle that is held in one hand, while the other hand engages the knob 18 of the crank and turns the crank to rotate the propeller.

To simulate motor noise while the propeller is turning, a noise-maker is provided, the same consisting in a leaf or blade 21 having a flattened end portion 22 secured to the side of the body 1 by screws 23 or other fastening elements, and provided with a free end which projects forwardly into position to be engaged by spaced pins 20 projecting inwardly from the back of the hub 7 of the propeller. When the propeller is rapidly spun by rotation of the crank 17, the striking of the leaf or blade 21 against the pins 20 will create a sound in simulation of airplane motor noise, so that each time that the propeller is rotated it will be accompanied by this sound.

In addition, means is provided by which sounds in simulation of machine-gun fire may be made while the propeller is being rotated. For this purpose is provided a blade 25, pivotally secured at 26 to one side of the body 1 and having a free end adapted to be brought into contact with the pins 24 provided on the pulley 15. For moving the free end of the blade 25 into operative or noise-making position, a trigger 28 is provided, said trigger being of bell-crank form and being pivoted to the body 1 at 29. The trigger is formed with the lifter arm 30 which is located below the blade 25 so that when the trigger is pressed, the lifter arm 30 will raise the blade upwardly into operative position to cause its free end to be sprung by each of the pins 24 as the pulley 15 is rotated. As each pin 24 passes the blade 25, which is flexible, it will flex the blade and cause it to be brought smartly or with a snap, against a stop-strip or abutment 27 secured to the side of the body 1 above the blade 25. The striking of the blade 25 against the abutment 27 will create a sharp noise, so that when the pulley is rapidly rotated and these sounds occur in rapid succession, the noise of machine-gun fire will be simulated. This noise will occur only

while the trigger is pressed, since the blade 25 will normally descend away from the pins 24 unless it is held upwardly in position to be flexed by the pins, by pressure on the trigger.

From the foregoing, the operation of the toy will be readily understood. In using the toy, the child supports it by one hand engaging the handle 19 while the other hand manipulates the crank 17 to cause rotation of the propeller through the drive means heretofore described. While the propeller is being rotated, the noise-maker, consisting of the elements 20 and 21, will cause a sound to simulate motor noise. When desired, the child may simulate machine-gun fire by pressing the trigger 28 to cause the lifter arm 30 to lift the blade 25 into operative engagement with the pins 24, causing the blade to strike against the stop-strip 27 and produce a series of sharp noises, which will continue as long as pressure is maintained on the trigger and will cease upon release of such pressure. Thus, through the mechanism described, and by the simple rotation of a single crank, rotation of the propeller, simulated motor noise and the sound of machine-gun fire is produced.

The device shown and described herein is illustrative since many modifications in design and structure may be readily made without departing from the spirit of the invention. For example, all of the operating parts of the toy may readily be housed in a hollow body or fuselage for the toy; a shaft or other drive may be substituted for the cord or belt drive disclosed; the position of the operating handle or crank may be changed materially; a spring motor or other source of motor power to drive shaft 16 may be used; the noise-making devices may be located at positions other than those disclosed and may be operated by other parts of the drive mechanism, and many other changes, apparent to those skilled in this art may be made without departing from the invention as defined by the annexed claims.

What I claim is:

1. A toy resembling an airplane, a propeller mounted thereon, a crank and means operated thereby for rotating the propeller, a noise-maker in simulation of machine-gun fire operated by crank rotation and normally inoperative, and trigger means for rendering said noise-maker operative during rotation of the crank.

2. A toy of airplane form including a rotating propeller, a crank and means by which the propeller is rotated by manual operation of the crank, a noise-maker in simulation of motor noise operated by crank rotation, a noise-maker in simulation of machine-gun fire also operated by crank movement but normally inoperative, and a trigger for rendering the last-mentioned noise-maker operative whenever desired during rotation of the crank.

3. In an airplane toy, a propeller and means for manually rotating the same, said means including a noise-maker to simulate machine-gun fire, said noise-maker being normally inoperative during propeller rotation, and means by which said noise-maker may be intermittently operated during propeller rotation.

4. An airplane toy having a rotating propeller, manually operated means for rotating the propeller, a motor-sound noise-maker set in operation by the propeller-rotating means, a machine-gun noise-maker operated by the propeller-rotating means, and means by which the machine-gun noise-maker may be maintained in either

operative or inoperative condition during operation of the propeller-rotating means.

5. A toy of the character described comprising, a body, a propeller shaft rotative thereon, a drive shaft, a crank for rotating the drive shaft, drive means between the drive shaft and the propeller shaft by which the propeller is rotated on operation of the crank, a noise-maker operated by said drive means to simulate motor noise, a second noise-maker operated by said drive means to simulate machine-gun fire, both of said noise-makers being operative while the crank is being turned to rotate the propeller, one of said noise-makers including means by which it may be rendered operative or inoperative at will without interrupting the operation of the other noise-maker.

6. A toy of the character described comprising, a body, a propeller shaft rotative thereon, a drive shaft, a crank for rotating the drive shaft, drive means between the drive shaft and the propeller shaft by which the propeller is rotated on operation of the crank, a noise-maker operated by said drive means to simulate motor noise, a second noise-maker operated by said drive means to simulate machine-gun fire, both of said noise-makers being operative while the crank is being turned to rotate the propeller, the noise-maker for simulating machine-gun fire including means by which it is caused to be inoperative or operative at will during propeller rotation and without interrupting the operation of the motor-sound noise-maker.

7. A toy of the character described comprising, a body, a propeller mounted for rotation thereon, a shaft on which the propeller is mounted, a noise-maker to simulate motor noise, said noise-maker comprising a fixed element on the body and striking means therefor driven by the propeller shaft, a hand-crank and means operated thereby for rotating the propeller shaft, said means including movable noise-making elements for simulating machine-gun fire, controlled striking means co-operating with the last-mentioned noise-making elements, and a trigger for causing said controlled striking means to become operative at any selected time during operation of the propeller-rotating means.

8. A toy of the character described comprising, an airplane body, a handle by which the same is held, a propeller shaft rotatively mounted in the body, a pulley secured on said shaft, a drive shaft means for manually rotating said drive shaft, a pulley on said drive shaft, a belt connecting the last-mentioned pulley with the pulley on the propeller shaft whereby manual rotation of the drive shaft will rotate the propeller shaft, a noise-maker to simulate motor noise, said noise-maker being operated by rotation of the propeller shaft and being continuously operative during rotation of the propeller shaft, a noise-maker for simulating machine-gun fire, the last-mentioned noise-maker including parts operative from the drive shaft, and means by which said parts are caused to be effective or ineffective to make a noise during rotation of the drive shaft.

9. A toy resembling an airplane and having a rotating propeller, means for rotating the propeller, a noise-maker for simulating motor noise operated during propeller rotation, a noise-maker for simulating machine-gun fire, and means by which the latter noise-maker is caused to be effective or ineffective to make a noise during propeller rotation.
